UNITED STATES PATENT OFFICE

NORTH H. LOSEY, OF AKRON, OHIO

VACUUM-SWEEPER CONSTRUCTION

Application filed December 30, 1925. Serial No. 78,333.

This invention relates to vacuum or suction sweepers in which the mouth or opening of the sweeper is provided with a brushing or beating element rotated by the motor which drives the suction fan. Heretofore, in sweepers of this type, a single rotating brush has been employed which extends across the opening in the sweeper, the brush being provided with a plurality of tufts arranged in a spiral formation about the central shaft. While this form of brush may possess certain advantages, it is the object of the present invention to improve upon such construction to obtain an improved beating and sweeping action.

Briefly stated, my invention consists in the provision of a plurality of beating, or beating and sweeping elements which are carried upon a main rotating member or rotor at some distance from the axis thereof so that as the member rotates the beaters strike the uplifted carpet a series of separate blows. The beaters are preferably rotatable upon their own axes so that they do not injure the carpet.

The beaters may be in many different forms, the preferred form being shown herein as brushes, but it will be appreciated that other beaters may be substituted therefor.

In the drawings in which is shown the preferred form of the invention:

Figure 1 is a view of any well known or standard form of suction sweeper equipped with my improved beating and brushing device;

Figure 2 is a section on the line 2-2 of Figure 1;

Figure 3 is an enlarged cross-section of the rotary member showing the manner of mounting the beater therein; and

Figure 4 is a cross-section on the line 4-4 of Figure 3.

In the drawings, 1 represents the usual head or frame of a motor-operated suction sweeper, the motor shaft being indicated at 2 and the mouth or opening for the sweeper being indicated at 3. The supporting rollers for the sweeper are indicated at 4.

The improved beater is located directly over the mouth of the suction sweeper and

is in the form of a rotor indicated in general by the numeral 5. It comprises a central shaft 6 which is mounted in the usual bearings 7 at the side of the head 1. As shown, the shaft 6 carries a plurality of spaced disks or bearing plates 8 which form the bearings for the several beater elements. In the preferred form of the invention, these beater elements are shown as small, rotatable brushes 10 which are distributed along the shaft and spaced about the rotor 5 at equal angular locations. Each brush is mounted at one end in a bearing 11 mounted in a disk 8. The other end of the brush is mounted in a removable bearing 12, the rear face of which is provided with a lug 13 which is adapted to enter a slot 14 in the disk 8. A small set screw 15 secures the bearing in position. A brush may be removed for cleaning or replacement by first removing the screw 15 and then lifting out the bearing 12 and the brush. The ends of the brush shafts are preferably seated in friction and noise deadening bearings 21 which may, in turn, be mounted in a sponge rubber pad 22. This arrangement serves to secure a quiet operation of the beaters and exerts a slight friction thereon to insure a positive brushing action.

The rotor is actuated from the motor shaft 2 by a continuous belt 16 which passes over pulleys 17 at the ends of the shaft 6, being guided by a plurality of idler pulleys 18 located on supports 19 about the underside of the head. Certain of these supports may be spring actuated as shown at 20 in Figure 1 for the purpose of maintaining tension in the belt. This construction is considered to be an improvement over prior forms in which the pulley upon the brush shaft is located at the center of the brush. The present arrangement gives a greater effective sweeping area as the drive pulleys are located at the ends of the opening rather than at the center.

The features of advantage over prior forms of suction sweepers will be readily understood. The rotating beater elements arranged at the periphery of the rotor 5 strike a plurality of rapid blows on the up-raised carpet at the mouth of the suction

sweeper. The feature of mounting the beating and brushing elements so that they may rotate prevents any destructive action upon the carpet.

5 The provision of complete disks about the shaft is non-essential. The disks, however, are believed to be preferable, for by their use it is possible for the manufacturer to dispense with the guards 25 which are usually employed in suction sweepers. The arrangement of the driving belt as shown is preferred, although any other suitably located belt may be substituted. Other forms of beaters may be used in place of the brushes and such further modifications may be made as found desirable or advisable.

What is claimed is:

1. In a motor driven vacuum sweeper, a driven rotor located at the suction opening 20 of the sweeper, and a rotatable brush carried by the rotor at a distance from its axis.
2. In a motor driven vacuum sweeper, a rotor located at the suction opening of the sweeper, driving means for the rotor, a plurality of spaced supporting members carried by the rotor, and brushes located between the members at a distance from the axis of the rotor and rotatable independently of one another.
3. In a motor driven vacuum cleaner, a driven rotor located at the suction opening of the cleaner, a plurality of separate rotatable beating elements carried by the rotor at a distance from the axis thereof, and friction 35 bearings on which the elements are journaled upon the rotor in such a manner as to offer a slight frictional resistance to rotation.
4. In a motor driven vacuum sweeper, a driven rotor located at the suction opening 40 of the sweeper, and a plurality of separate rotatable brushes of less diameter than the rotor, said brushes being arranged in spaced relation along the rotor and with their axes arranged in different angular positions thereon.
5. In a motor driven vacuum cleaner, a driven rotor located at the suction opening of the cleaner, and a rotatable beating element carried upon the rotor, the axis of the beating 50 element being fixedly disposed at a distance from the axis of the rotor, the element being rotatable completely about its own axis.
6. In a motor driven vacuum cleaner, a driven rotor located at the suction opening of the cleaner, and a plurality of rotatable beaters carried by the rotor, the axes of the beaters being in fixed positions upon the rotor and located at a distance from the axis of the 60 rotor and distributed along the rotor in different angular positions about the rotor axis, the elements being completely rotatable about their own axes.
7. In a motor driven vacuum cleaner, a driven rotor located at the suction opening of the cleaner, said rotor including a plurality 65

of spaced supporting members, and beating elements journaled in fixed positions between the members and rotatable independently of one another, the elements being completely rotatable about their own axes.

8. In a motor driven vacuum cleaner, a 70 driven rotor located at the suction opening of the cleaner, and a plurality of separate beating elements carried by the rotor, the axes of the elements being fixed at a distance from the axis of the rotor and at angularly spaced locations thereon, the elements being rotatable completely about their own axes.

9. In a motor driven vacuum cleaner, a driven rotor located at the suction opening 80 of the cleaner, and a plurality of rotatable beating elements of less diameter than the rotor and located with their axes in a cylinder about the axis of the rotor, said elements being rotatable completely about their own axes. 85

10. A vacuum cleaner including a suction nozzle having a driven means adjacent the inlet thereof, and a brush eccentrically journaled upon the driven means to move toward and from the inlet, the journal of said brush being frictional and permitting the brush to rotate relatively to the driving means by engagement of the brush with the surface being cleaned.

11. A vacuum cleaner including a suction 95 nozzle having a driven means adjacent the inlet thereof, and a beater eccentrically journaled upon the driven means to move toward and from the inlet, the said beater being rotatable completely about its own axis, the 100 journal of said beater being frictional and permitting the beater to rotate relatively to the driven means by engagement of the beater with the surface being cleaned.
